ARCH SUPPORT

Filed Aug. 7, 1930

INVENTOR.

Charles H. Freeman

BY

Thomas D. Daniels

ATTORNEY.

UNITED STATES PATENT OFFICE

CHARLES H. FREEMAN, OF DETROIT, MICHIGAN

ARCH SUPPORT

Application filed August 7, 1930. Serial No. 473,549.

My invention relates to a new and useful improvement in an arch support so arranged and constructed as to perform the functions of the usual arch support and also to provide a cushion whereby standing, walking, and the like is made more comfortable and the feet eased of the strain to which they are ordinarily subjected.

It is an object of the present invention also to provide an arch support sufficiently yieldable as to permit its shaping itself to the contour of the foot so as to place under the foot at those points where most needed sufficient support to relieve the user of pain and discomfort.

Another object of the invention is the provision of an arch support formed from sponge rubber or the like and provided with a covering for resisting wear.

Another object of the invention is the provision of an arch support of this class provided with air pockets to assist the circulation of air around, under and into the arch support when it is worn so as to prevent the perspiring of the feet.

Another object of the invention is the provision of an arch support having an enlarged portion engageable with the arch of the foot and a raised portion positioned forwardly thereof for engaging the under surface of the foot.

Another object of the invention is the provision of an arch support which may be economically manufactured, durable and efficient in use, and easily inserted into the shoe in position for wearing.

Other objects will appear hereinafter.

The invention consists in the combination and arrangement of parts hereinafter described and claimed.

The invention will be best understood by a reference to the accompanying drawing which forms a part of this specification, and in which,

Fig. 1 is a bottom plan view of the invention.

Fig. 2 is a side elevational view of the invention.

Fig. 3 is a sectional view taken on line 3—3 of Fig. 1.

Fig. 4 is a sectional view taken on line 4—4 of Fig. 1.

Fig. 5 is a sectional view taken on line 5—5 of Fig. 1.

The invention comprises a main body 9 which is formed from sponge rubber or other sufficiently yieldable material which will resume its normal shape after being relieved of pressure which has a tendency to force it out of its normal shape. A covering 8 is mounted on the upper surface of the body 9. This covering 8 is formed from leather or other suitable flexible material which, while permitting the arch support to assume under pressure the shape desired, will also serve to resist wear. Formed on the body 9 intermediate its ends and adjacent one side, is an enlargement 10 which serves to provide the necessary body for forcing the arch support into engagement with the under surface of the foot at the arch and afford the support necessary for the foot at the arch portion. Extending transversely of the arch support and formed in the enlargement 10 at opposite sides of the transverse medial line thereof are passages 11.

An enlargement or outwardly extending projection 12 is formed on the under surface of the body 9 adjacent the forward end thereof and positioned substantially centrally between the side edges of the arch support. The formation of the enlargement 12 forwardly of the enlargement 10 provides the valley 13. The enlargement 12 is provided to exert additional pressure and presents additional support centrally of the ball of the foot so as to relieve the wearer of pain resulting at this point.

In use, the arch support is positioned in the shoe with the body 9 faced downwardly so that the foot will engage the leather covering 8. Since the entire body is quite flexible, the arch support will conform itself to the shape of the foot, placing the necessary additional pressure on the foot at those points which weak arches require. In walking, the sponge rubber or body 9 will, when the weight of the body is placed on the foot, be compressed or slightly flattened and caused to flow into snug engagement with the foot thus

assuring a uniform pressure over the base of the foot. When the foot is lifted and the weight of the body removed therefrom, the body 9 will resume its normal shape, and this compressing and releasing of the body 9 from pressure will cause a suction to be set up around the foot and around the arch support. This air movement is also assisted by the pockets or passages 11 so that an excessive 10 heating of the foot resulting from the use of the arch support is prevented.

The enlargement 10 inclines from its transverse medial line to the rear and the forward ends of the main body and also inclines from 15 one edge of the main body toward the other.

The projection or enlargement 12 is formed so that an incline in all directions is effected, this enlargement or projection 12 therefore being more nearly semi-spherical than any 20 other regular geometrical formation. The presence of the valley 13 also assists in the air movement when the weight is placed upon the arch support and then released therefrom.

An arch support constructed in this manner 25 has proven most comfortable to those afflicted with weak arches and affords the wearer a maximum ease and comfort because of the cushioning effect. Also because of the movement or flowing of the arch support into 30 various shapes to conform to the contour of the foot, the arch support eventually will result in a strengthening of the muscles of the foot and afford the wearer permanent relief from weak arches.

35 While I have illustrated and described the preferred form of construction of my invention, I do not wish to limit myself to the precise details of structure shown but desire to avail myself of such variations and modifications 40 as may come within the scope of the appended claim.

Having thus described my invention, what I claim as new and desire to secure by Letters Patent is:

45 In an arch support of the class described, a main cushioning body; an enlargement projecting outwardly from the under surface of said main body and tapering in thickness toward the center of said main body, there 50 being projected inwardly of said main body from one of the side faces thereof between the upper and lower surfaces thereof and at opposite sides of the transverse medial line of said enlargement a plurality of spaced 55 passages.

In testimony whereof I have signed the foregoing specification.

CHARLES H. FREEMAN.
